ATTORNEY

UNITED STATES PATENT OFFICE

JOSEPH MUROS, OF NEW YORK, N. Y., ASSIGNOR, BY MESNE ASSIGNMENTS, TO GILLETTE SAFETY RAZOR COMPANY, OF BOSTON, MASSACHUSETTS, A CORPORATION OF DELAWARE

SAFETY RAZOR

Application filed October 6, 1928. Serial No. 310,782.

The present invention relates to improvements in safety razors, and more particularly to the blade holder and blades thereof.

It is a common practice at present in the safety razor trade to manufacture and sell blades which fit the blade holders of other manufacturers. The user may, therefore, purchase several makes of blades fitting his blade holder to the exclusion of the blades manufactured by the maker of the holder. While under certain circumstances there is nothing wrong with this practice, an extended study of the field reveals the fact that the general public is apt to blame the manufacturer of the holder for the faults of the blades, resulting in great injury and damage to the reputation of the holder manufacturer.

The main object of the present invention is to provide a blade holder and blade construction which effectively precludes this general practice.

Another object of the invention is to provide a simple and efficient blade holder and blade construction which is capable of manufacture on a commercial scale, or in other words one which is not so difficult to make as to be beyond the reasonable cost of such a contrivance.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

A few of the many possible embodiments of the invention are illustrated in the accompanying drawings, in which:—

Figure 1 is a front elevation of a safety

razor constructed in accordance with the present invention; Fig. 2 is a section taken on line 2—2 of Fig. 1; Fig. 3 is a top plan view of the blade supporting element of the razor; Fig. 4 is a bottom plan view of the blade 50 clamping element thereof; Fig. 5 is a plan view of the improved blade, showing in dotted lines the blade positioning lugs of the holder in operative relation to the elements of the blade cooperating therewith; and Fig. 6 is 55 a similar view of a modified blade.

Referring now first to Figs. 1 to 5, inclusive, of the drawings, which illustrate the application of the invention to a safety razor of the Gillette type, the numeral 10 indicates 60 a blade supporting plate, suitably curved along its longitudinal edges and provided with teeth 11, forming guards for the well-known purpose. On this plate is adapted to rest a transversely flexible blade 12, having 65 longitudinal cutting edges 13. This blade is positioned upon its support by lugs 14 on a clamping cap 15, which lugs extend through registering openings 16 and 17 in the blade and supporting plate, respectively, the said 70 lugs and the said openings being of a configuration to be more fully described hereinafter.

The cap is provided with a concaved under-face 18, its longitudinal edges resting on the 75 upper face of the blade. From the under-face of the cap projects centrally a screw-threaded spindle, not shown, which extends through registering apertures 19 and 20 in the blade and supporting plate respectively. 80 The razor is provided with a handle 21, having a screw-threaded bore, not shown, the threads of which mesh those of the spindle above referred to. Inasmuch as the construction and operation of the said screw-threaded bore and spindle are well-known, they being embodied in the razor of the type known in the trade as the Gillette razor, a detailed description of these elements seems 85 to be unnecessary.

The positioning lugs 14 are each provided at their free ends with an enlarged head 22, the body portion 23 of each lug being cylindrical and, preferably, having a size in transverse cross-section which corresponds to that of the ordinary positioning lugs commonly used on razors of the Gillette type. The purpose of this arrangement will appear hereinafter. The head 22 of each positioning lug is polygonal in transverse cross-section. In the embodiment of the invention illustrated in Figs. 1 to 3, inclusive, of the drawings, the bounding figure of the transverse cross-section of said head is a regular polygon, more particularly a square, although it may be any other polygon, as will appear more fully hereinafter. The said bounding figure is of a size that the circle, forming the bounding figure of the transverse cross-section of the body portion of a lug, may be inscribed into the same. The length of the body portion of each lug exceeds considerably the thickness of the blade 12, so that the said body portion extends into the opening 17 in the supporting plate 10 in the assembled positions of the elements of the razor before the blade is flexed in the well-known manner. The purpose of this arrangement will also appear hereinafter.

30 The registering openings 17 and 16 in the supporting plate 10 and razor blade 12, respectively, are alike in configuration. Their configuration is congruous with the transverse cross-section of the head of a lug cooperating therewith. As appears more specifically from Fig. 5 of the drawings these openings are square. Of course, the openings 17 in the supporting plate 10 may be of any other shape, for instance circular and of a size to accommodate the head of a lug.

As appears from Fig. 5 of the drawings, the openings 16 in the blade 12 are so arranged that the edges thereof, that is to say the sides of the polygons, are out of parallelism with the cutting edges of the blade. Consequently, the edges of the head 22 are out of parallelism with the longitudinal axis of the clamping cap 15.

50 In use, the razor is assembled in the usual manner, Figs. 1 and 2 illustrating the parts assembled in the positions which they occupy for shaving. It will be noted that when the parts are in the positions before flexing of the blade for shaving, the edges of the polygonal openings 16 in the razor blade already abut against the cylindrical body portions of the supporting lugs, so that, when the blade is flexed by screwing home the handle 21, the blade is effectively prevented from shifting both longitudinally and transversely on the supporting plate of the razor, or in any other direction save in the direction of the axes of the positioning lugs.

60 By reason of the construction of the heads 65 of the positioning lugs and the configuration

of the openings 16 in the blade, and the specific location of the edges of the said openings in relation to the cutting edges of the blade, it is obvious that, if it is attempted to design a blade to fit the razor herein described, such blade would either have to have circular openings circumscribing the polygonal openings in the blade or be polygonal and circumscribing the polygonal openings in the razor blade. In either case, however, the blade would shift transversely on the supporting plate when the handle of the razor is screwed home to secure the blade in shaving position, because the circumscribing circle or polygon would not contact at a plurality of points with a positioning lug.

If the body portion of each supporting lug were not of a length so that the outer end of said body portion were disposed within an opening 17 in the supporting plate when the elements of the razor are assembled before flexing of the blade for use, obviously any blade having either circular or polygonal openings circumscribing the blade openings herein described would fit the razor and would be prevented from shifting on the supporting plate.

It is obvious that, while herein square supporting-lug heads and square lug receiving openings in the razor blade have been described, heads and openings of any other suitable configuration may be made use of without departing from the invention. It is, however, essential that the openings in the blade be polygonal, either regular or irregular, and correspond in size and configuration to the transverse cross-section of the head of a lug employed on the razor; that the said openings be of a configuration that the circle bounding the transverse cross-section of a body portion of a positioning lug be adapted to be inscribed in the same; and that not more than one of the bounding lines of the polygonal opening shall be in parallelism with the cutting edges of the blade.

In the modification illustrated in Fig. 6, the positioning-lug receiving openings 25 are rhombiform, that is to say they are in the shape of equilateral parallelograms. These openings are in the form of irregular polygons, but are adapted to be inscribed by a circle, as clearly appears from Fig. 6 of the drawings. The co-operation of the blade described in Fig. 6 of the drawings with the heads of the positioning lugs is obvious from the foregoing.

What I claim is:

1. The combination with a blade having one or more openings, of a blade holder, a corresponding number of positioning lugs on said holder for cooperation with said openings, each lug including a body portion fixed at one of its ends to said holder and being provided at its other end with an enlarged head having a polygonal transverse cross-

section into which the bounding figure of the transverse cross-section of said body portion is inscribed, the configuration of each opening in said blade corresponding to that of the 5 transverse cross-section of the head of a lug co-operating therewith.

2. In a combination according to claim 1, said body portion being of uniform diameter throughout its length and its length exceeding the thickness of said blade.

Signed at New York, in the county of New York, and State of New York, this 5th day of October, A. D. 1928.

JOSEPH MUROS.
